AIR-CONDITIONING APPARATUS

Erving B. Morgan, Grand Rapids, Mich., assignor
to American Seating Company, Grand Rapids,
Mich., a corporation of New Jersey

Application March 28, 1938, Serial No. 198,457

1 Claim. (Cl. 98—37)

The present invention relates to air-conditioning apparatus; and its object is to provide such an apparatus for supplying pure air of proper temperature to rooms as theatre auditoriums and the like, which shall be simple and economical in construction, readily installed, effective in operation, and particularly, which may be readily mounted in connection with the chairs in such auditoriums.

10 This and any other objects hereinafter appearing are attained by, and the invention finds preferable embodiment in, the illustrative apparatus and the various parts thereof particularly described in the body of this specification and 15 illustrated by the accompanying drawing, in which:

Figure 1 is a view in perspective of a damper and the mounting therefor;

Figure 2 is a side view thereof shown partially 20 in section taken on line 2—2 of Figures 1 and 3;

Figure 3 is a plan view of the damper and a sectional view of its mounting taken on line 3—3 of Figures 2 and 4;

Figure 4 is a transaxial sectional view of the 25 same taken on line 4—4 of Figures 2 and 3;

Figure 5 is an elevational view in perspective of portions of an air conduit, mounting means 30 therefor and a damper with its mounting in the conduit, a portion of the floor through which the conduit extends being broken away;

Figure 6 is an elevational view thereof, the floor 35 being shown in vertical section taken on line 6—6 of Figure 5;

Figure 7 is a horizontal sectional view of parts 40 shown in Figures 5 and 6 taken on line 7—7 of these views.

In the drawing my apparatus is shown in connection with a room—a theatre auditorium—for air-conditioning the same by supplying pure or clean air of proper temperature thereto or withdrawing impure air therefrom.

A conduit for the air is shown extending through a wall—the floor 1—of the room, comprising an inner portion or section 2 in the floor 45 and an outer portion or section above the floor, this outer section, in the room, comprising separate lateral halves 3, 4, only one of which is (for the sake of clearness) shown in Figure 5. As illustrated, each of these halves has, desirably and for economizing space, an inner (lower) portion 5 and a narrower outer (upper) portion 6, these portions having concavo-convex side walls 7, 8 and top walls 9, 10 respectively, the side walls 50 of the outer (upper) portions 6 curving in an arc of greater radius than that of the curvature

of the side walls of the inner (lower) portions 5, as best seen in Figure 7. These side walls have air passages 11, 12 therethrough. The halves, assembled with their concave sides mutually adjacent and connected by a bolt 13 extending therethrough provided with a nut 14, are held in place by and between a pair of supporting members 19, 20 extending parallelly from, and fastened as by screws 15 on, the room side of the wall or floor, the vertical edges 16 of these halves 5 engaging behind a pair of opposite vertical ribs 17 of said members as indicated in Figure 7, the said members being the leg portions of a standard 21 supporting the seats and the backs of a pair of sidewise adjacent chairs (not shown) in the 15 auditorium.

In the circular lining 22 of the inner section 2 of the conduit (which extends through the floor) a damper with its mounting is removably seated between said members 19, 20 and is turnable 20 therein for directing the air issuing therefrom. This mounting comprises a pair of diametrically opposite downwardly extending arm portions 23 having ledges 24 resting on the floor or on the upper edge of the lining 22, and connecting upper and lower cross bars 25, 26 forming stops for limiting the turning movement of the damper as indicated in Figure 4. A spindle 27 seated in openings 28 in the arm portions 23 extends diametrically through the damper 29 between its 30 oppositely extending ears 30, 31 with a coiled spring 32 surrounding the spindle and pressing between one of the arm portions 23 and the edge of the damper to frictionally hold the same in turned position.

It will be seen that my air-conditioning apparatus may be readily installed in theatre auditoriums and the like, the outer upper section of the conduit being removably held by and between the leg portions of one of the standards of a chair therein; and that thus installed the said section is located in a position wherein it interferes slightly or not at all with ready access to the chairs and occupies little space in the auditorium; and that the parts of the apparatus may, when necessary or desirable, be readily removed and replaced.

The invention being intended to be pointed out in the claim, is not to be limited to or by details of construction of the particular embodiment 50 thereof illustrated by the drawing or hereinbefore described.

I claim:

An apparatus of the class described for conditioning the air in a room furnished with chairs 55

having spaced legs; an air conduit comprising a cross-sectionally circular section extending through the floor of the room and a section in the room comprising separate lateral halves having 5 concavo-convex side walls with air passages therethrough, the mutually adjacent opposite vertical edges of said halves assembled with their concave sides mutually adjacent being engaged by said legs for holding said halves between them;

a damper turnable to conduit closing and opening positions; a mounting for the damper turnable in the first mentioned section, comprising downwardly extending arms connected by cross bars, a spindle for the damper supported at its ends on the arms respectively and ledges resting on the floor to support the damper and its mounting turnably on the floor. 5

ERVING B. MORGAN.
